AUTOMATIC DISPLAY DEVICE FOR
PHONOGRAFS

Jerry Levy, New York, N. Y., assignor, by direct and mesne assignments, of ten per cent to Lester Soman, and twenty-five per cent to Andrew D. Weinberger, both of New York, N. Y., and five per cent to Leon Kellman

Application December 22, 1939, Serial No. 310,493

7 Claims. (Cl. 88—27)

This invention relates to an automatic display device for phonographs, especially phonographs which are arranged to play a plurality of records individually or in any desired order, and its object is to combine and coordinate such a phonograph with a picture display appropriate to the particular record which is being played at any given time.

A more specific object of the invention is to provide, in combination with a phonograph of the above type, a simple and inexpensive mechanism for automatically selecting and displaying, simultaneously with the playing of each record, a complementary picture of the orchestra leader, assembled band, vocal artist or the like, whose work is being rendered at that particular time.

My invention is particularly applicable to coin-controlled phonographs containing a plurality of sound records, the recordings being either on phonograph discs or cylinders or even on one or more strips of film, the records being automatically selected and played individually or in any desired sequence without any attention or supervision other than by initially setting the selective mechanism. In the usual machine of this type the operator merely inserts a coin in a slot and then pushes a button opposite the name of the particular piece of music which he desires to play.

Automatic phonographs of the above type are widely used to supply music in restaurants, clubs, dance halls, etc. Many people, especially those in the younger dancing set, have marked preferences for the music of certain orchestra leaders of established reputations, and their selections of dance music, songs, etc., are usually guided by such preferences. My invention caters to the requirements of such people, and, by automatically displaying an attractive illuminated picture of one's favorite artist on the machine simultaneously with the playing of each record, not only provides a visual interpretation which enhances the aesthetic appeal of the music, but also increases the "sales appeal" of the machine with resulting increased revenue to the owner.

Although my invention is not to be limited to any particular type of phonograph, I shall, for purposes of illustration, describe it in its application to an automatic disc record machine of standard construction which is arranged to select any one of a number of records, swing it to a position where it is picked up by a turntable, after which the record is played and then removed from the turntable and returned to its initial inoperative position. In carrying out my

invention I provide a machine of this type with a picture projection screen located on a conspicuous part of the cabinet, and upon which the pictures or insignia allotted to the various records are to be shown. The display mechanism includes, in conjunction with a suitable lens system, a movable device carrying a plurality of pictures corresponding to the number of records in the machine, each picture being a characteristic view of an orchestra leader or the like or being otherwise appropriate to the particular record with which it is associated.

In a preferred form of the invention, disclosed herein for purposes of illustration, the various pictures which are adapted to be projected upon the screen are mounted about the periphery of a rotatable wheel which is adapted to be rotated past the lens system in such a way that each picture, when selected, will be properly and accurately centered for projection upon the screen and will remain in such position throughout the playing of the selected record. In this embodiment of the invention the wheel carrying the pictures is actuated by the record selecting mechanism, and upon the completion of the selecting operation a lamp is automatically lighted to project the selected picture upon the screen as the record starts to play. After the record has been played the selecting mechanism returns to normal and the projection lamp is automatically extinguished, and in its place suitable colored lamps may be automatically energized to illuminate the projection screen with an attractive iridescent display of color until such time as the machine is again set in operation.

Another important feature of my invention resides in a special construction of the picture supporting wheel which, as hereinafter described, enables pictures on ordinary motion picture film to be inserted and removed instantly at the time the phonograph records are changed.

These and other features and advantages of the invention will be described in connection with the accompanying drawings, in which:

Fig. 1 is a vertical sectional view of a combination automatic phonograph and display device embodying the invention;

Fig. 2 is a detail section taken on line 2—2 of Fig. 1;

Fig. 3 is a plan view of the picture selecting and projecting mechanisms;

Fig. 4 is a section taken on line 4—4 of Fig. 3, showing the operating mechanism for the various lamps;

Fig. 5 is a sectional view taken on line 5—5 of

Fig. 3, showing the construction and mounting of the picture carrying wheel and associated parts;

Fig. 6 is a detail section taken on line 6—6 of Fig. 4;

Fig. 7 is an enlarged fragmentary view of the picture carrying wheel;

Fig. 8 is a sectional view taken on line 8—8 of Fig. 7, showing a picture secured in place on the wheel;

Fig. 9 is a similar sectional view showing how the pictures are inserted and removed through the periphery of the wheel;

Fig. 10 is a transverse section taken on line 10—10 of Fig. 7; and

Fig. 11 is a diagram of the electric lamp circuits.

In Fig. 1 of the drawings I show an automatic coin-controlled phonograph of standard construction mounted in a cabinet 1 and including the usual turntable 2 carried by a vertically movable shaft 3 supported by a suitable bearing member 4. The mechanism for actuating shaft 3 to raise and lower turntable 2 includes a yoke 5 which is secured to bearing 4 by screw 6, and a pin 7 which connects the sides of yoke 5 and is pivotally connected to a bell crank lever 8 as shown in Fig. 1.

The phonograph records 10 are placed in annular record carriers or trays 12 of standard construction, and each of these record carriers has an arm (not shown) extending through one of a plurality of horizontal slots 13 in a cylindrical casing 14 which contains a rotatable shaft 15 extending downwardly through the center thereof as shown in Fig. 1.

I shall now describe the mechanism for selecting and initiating the playing of the records. A bar 17 is slidably mounted on shaft 15 by means of arms 18 and 19. This bar has an elongated longitudinal slot 20 and at its upper end carries a projection or screw 21 which is adapted to engage selectively with the arms (not shown) of the record carriers 12 extending through the slots 13 of cylindrical casing 14. The means for operating the record carriers 12 also includes an arm 22 which is fastened to the shaft 15 and extends through the slot 20 in bar 17, and at its outer end the arm 22 is pivotally connected to a lever 23. The mechanism for operating the record carriers 12 also includes a U-shaped member 24 which is mounted on shaft 15 and is connected by link 25 to a lever 26 which is actuated by the selecting apparatus mounted in the casing 27 shown in Fig. 1. The phonograph apparatus so far described forms no part of my invention as it is of standard construction, being of the type shown, for example, in Patent #2,002,236 of May 21, 1935, and I have therefore shown only so much of such apparatus as will be necessary to an understanding of my invention.

A standard coin-controlled phonograph of this type is provided with a coin chute 28 and with a plurality of push buttons or plungers 29 corresponding in number with the phonograph records employed and appropriately labeled with the title of the record, including, usually, the name of the orchestra leader, vocal artist or the like represented on each individual record. The standard record selecting and playing mechanisms controlled by the coin and the selector buttons 29 are mounted in the casing 27. For the purpose of understanding my invention it is sufficient to note that when a coin is inserted in the chute 28 and one of the buttons 29 is actuated to se-

lect and play any given record of the group, the mechanism is set in motion to raise or lower the bar 17, as the case may be, causing the projection 21 on the upper end thereof to enter one of the slots 13 in the cylindrical casing 14 and engage the arm of the selected record carrier 12.

Thereupon the mechanism including shaft 15 and lever 23 is actuated to swing the selected record carrier out of line with the other record carriers and into alignment with the turntable 2 which is automatically raised by its shaft 3 and its associated mechanisms into a position where it enters the annulus of the selected record carrier 12 and engages the selected record 10 as indicated in dotted lines in Fig. 1. The turntable 2 rotates and the selected record is played, after which the turntable 2 returns to the normal position shown in Fig. 1, returning the previously selected record 10 to its carrier 12 which is thereupon swung back into its normal position in alignment with the stack of record carriers shown in Fig. 1. In standard automatic phonographs of this type, however, the record selector bar 17 and associated parts usually remain in the position to which they have previously been moved until such time as the machine is again operated to select and play either the same record or another record.

In accordance with my invention the automatic phonograph described above is provided with a projection screen 30 which is prominently located, for example in the front panel of the cabinet 1 where it is readily visible to the operator or audience. A casing 31 encloses the screen 30 within the cabinet and may contain a plurality of electric lamps 32 and 33, preferably of different colors, such as red and green, which are lighted when the phonograph is not playing, thereby causing the screen 30 to glow with an attractive iridescent light, as hereinafter described.

The projecting mechanism includes a lens system comprising a reflector 35, an adjustable lamp 36, a condenser lens 37 having suitable exterior cooling fins 38, a projection lens 39 and a shield 40, as shown in Fig. 3. The lens system and associated apparatus are mounted in a housing 42 having a suitable cover which may be opened to permit ready access to the parts.

The pictures or other insignia which are to be projected upon the screen 30 are carried by a wheel or disc 44 having its hub 45 keyed by set screw 46 to a rotatable shaft 47 suitably mounted on bearings 48 and 49 on a supporting frame 50 within the housing 42. The wheel 44, shown in detail in Figs. 7 to 10, is composed of two outer circular plates 52 and 53 of equal diameter, and an inner circular plate 54 of smaller diameter having spaced extensions or spokes 55, which serves as a spacer for the outer plates 52 and 53 and thereby forms a series of slots 56 about the periphery of the wheel 44 between the various spokes 55.

The surface of the wheel 44 is provided with a plurality of equally spaced openings 57, adjacent the periphery thereof, which constitute frames or windows for the various pictures which are to be projected upon the screen 30, these openings or frames 57 corresponding to the number of phonograph records employed in the machine. The individual pictures 60, preferably consisting of ordinary squares of motion picture film, are inserted through the peripheral slots 56 in the wheel 44 into registry with the respective openings or frames 57 as best shown in Figs. 8 and 9.

In order to hold the pictures 60 in place I provide a plurality of spring clips 61 which are mounted axially about the wheel 44, one for each picture frame, each clip being provided with a detent 62 which is adapted to enter a slot 63 in the plate 53 of wheel 44 to engage and hold its associated picture 60 when the spring 61 is depressed as shown in Fig. 8.

In order to disengage the detents 62 from the pictures I provide a plurality of small push buttons 65, one allotted to each clip 61 as shown in Figs. 7 to 9. The shanks of the push buttons 65 extend through holes in the wheel 44 into engagement with the respective spring clips 61, so that, when any button 65 is depressed as shown in Fig. 9, it forces the detent 62 out of its hole 63 against the normal tension of spring 61 thereby permitting the picture 60 to be withdrawn and changed as required. The wheel 44 is positioned between the condenser lens 37 and the projection lens 39 as shown in Fig. 3, so that, as the wheel shaft 47 rotates, the pictures 60 are brought into the proper position for projection upon the screen 30 as illustrated in Fig. 5.

I shall now describe the mechanism for rotating the picture wheel 44 in synchronism with the record selecting or changing mechanism, whereby the particular picture allotted to any given record is automatically brought into the proper position in the lens system for projection upon the screen 30 when the operator selects said record to be played. A cord 67 is fastened at one end to an extension 68 on the U-shaped member 24 of the record selecting mechanism, as shown in Fig. 1, and this cord passes over a plurality of idler rollers 70, 71, 72, 73 and 74, and thence over an adjustable cone pulley 76 to which the end 77 of said cord 67 is fastened as shown in Fig. 5. The adjustable pulley 76 is mounted on the rotatable shaft 47 which also carries the picture wheel 44 as previously described. It will thus be seen that when the U-shaped member 24, bar 17 and associated elements of the record selecting mechanism of Fig. 1 are raised to select a given phonograph record, the cord 67 will likewise be moved in a direction to turn the pulley 76, shaft 47 and picture wheel 44 until the picture allotted to the selected record is brought into registry in the lens system in the proper position for projection upon the screen 30. When the bar 17 and associated elements of the record selecting mechanism are lowered, the pulley 76 and consequently the picture wheel 44 are rotated correspondingly under the action of a suitable spring 79 one end of which is fastened to the frame 50 of the machine and the other end of which is secured to a suitable chain or other connecting link 80 which is secured to the shaft 47 as shown in Figs. 3 and 4.

The mechanism controlling the electric circuits of the colored screen lamps 32 and 33 and the lens lamp 36 is actuated by the apparatus for raising and lowering the turntable 2 of the phonograph. For this purpose the pin 7 carried by the yoke 5 of the turntable mechanism carries an extension 82 as shown in Fig. 1. Toward the end of the travel of the bell crank lever 8, during the raising of the turntable 2, the yoke 5 is moved to a position where the extension 82 of pin 7 engages a finger 83 of a slidable bar 84 having a longitudinal slot 85 tracking on pins 86 secured to the frame of the machine. The lower end of the slidable bar 84 is secured to a cord 88 which passes over idler rollers 89, 90 and 91 and is secured at its opposite end to a lever 92 which is

pivoted to the frame at 93, as shown in Figs. 1 and 6. The lever 92 has a forked end 95 which engages beneath an arm 96 forming part of a rocker arm 97 which is pivoted to the frame at 98 as shown in Figs. 4 and 6. The arm 97 has a U-shaped extension 99 carrying mercury switches 100 and 101, the switch 100 controlling the screen lamps 32 and 33 while the switch 101 controls the lens lamp 36. The arm 96 carries a detent 103 cooperating with a ratchet 104 which is keyed to the rotatable shaft 47 carrying the picture wheel 44 as shown in Figs. 3 and 4. When the detent 103 engages the teeth of ratchet 104, as in Fig. 4, the shaft 47 and picture wheel 44 are locked against rotation, and at such time one or another of the pictures 60 carried by the wheel 44 will be exactly centered in the lens system for accurate projection upon the screen 30, and under such conditions the rocker arm 97 is tipped toward the left as viewed in Fig. 4 so as to close the circuit of lens switch 101 and light the lens lamp 36 as illustrated in Fig. 11. However, when the cord 88 releases its tension on arm 92, as it does when the turntable 2 is lowered to its normal inoperative position, a spring 106 (Figs. 4 and 6) depresses arm 96, thereby withdrawing detent 103 from engagement with ratchet 104 and tipping the rocker arm 97 toward the right as viewed in Fig. 4, thus breaking the circuit of switch 101 and extinguishing the lens lamp 36 and at the same time operating switch 100 and energizing the screen lamps 32 and 33 over the circuit shown in Fig. 11. As illustrated in Fig. 11, the electric lamp circuit may be provided with a hand switch 107 for disconnecting the current when the machine is not in use.

It will be evident that many changes may be made in the details of construction and methods of operation herein shown and described without departing from the scope and spirit of the invention as defined in the appended claims.

The invention claimed is:

1. In an automatic phonograph of the type containing a group of records, selective means operable to automatically select a record from the group and to initiate the playing thereof, a picture projecting mechanism including a screen, a light source and a lens system for projecting pictures upon said screen, a movable picture display member containing a plurality of pictures adapted to be moved into the field of said lens system for projection upon said screen, each of said pictures being appropriate to an individual record, means actuated by said selective means for moving said display member into the field of said lens system in position to project the picture appropriate to the selected record upon said screen, and means actuated upon the completion of said selecting operation to illuminate said light source to project the selected picture upon said screen.
2. In an automatic phonograph of the type containing a group of records, a movable turntable, a record-changing mechanism for selecting said records and for moving the selected record into a position to be received by said turntable, operating means for said turntable for moving same into a position to receive the selected record from said record-changing mechanism, a picture projecting mechanism including a screen, a light source and a lens system for projecting pictures upon said screen, a movable picture display member containing a plurality of pictures movable in the field of said lens system for projection upon said screen, each of said pictures being appro-

priate to an individual record, means actuated by said record-changing mechanism for moving said display member into the field of said lens system in position to project a picture appropriate to the selected record upon said screen, and means actuated upon the completion of said selecting operation to illuminate said light source to project the selected picture upon said screen.

3. In an automatic phonograph of the type containing a group of records, selective means operable to automatically select a record from the group and to initiate the playing thereof, a picture projecting mechanism including a screen, a lamp, and a projection lens and condenser lens between said screen and said lamp, a rotatable picture display wheel containing a plurality of pictures rotatable directly between said projection and condenser lenses for projection upon said screen, means actuated by said selective means for rotating said wheel to bring a selected picture into registry in said projecting mechanism in position for projection upon said screen, and means actuated upon the completion of said selecting operation to light said lamp to project the selected picture upon said screen.

4. In an automatic phonograph of the type containing a group of records, selective means operable to automatically select a record from the group and to initiate the playing thereof, a picture projecting mechanism including a screen and a lens system for projecting pictures upon said screen, a rotatable picture display wheel containing a plurality of pictures rotatable directly in the field of said lens system for projection upon said screen, said wheel having a plurality of openings forming windows adjacent the periphery of the wheel and having slots in the peripheral edge for the ready insertion of pictures into registry with said windows, releasable spring clips on said wheel flexed to engage said pictures for clamping same in place at said windows, and means actuated by said selective means for rotating said wheel to bring a selected picture into the field of said lens system in position for projection upon said screen.

5. In an automatic phonograph of the type containing a group of records, selective means operable to automatically select a record from the group and to initiate the playing thereof, a picture projecting mechanism including a screen, a lamp, and a projection lens and condenser lens between said screen and said lamp, a rotatable picture display wheel containing a plurality of pictures rotatable directly between said projection and condenser lenses for projection upon said screen, said wheel having a plurality of openings forming windows adjacent the periphery of the wheel and having slots in the peripheral edge for the ready insertion of pictures into registry

with said windows, releasable spring clips on said wheel flexed to engage said pictures for clamping same in place at said windows, means actuated by said selective means for rotating said wheel to bring a selected picture into registry in said projecting mechanism in position for projection upon said screen, and means actuated upon the completion of said selecting operation to light said lamp to project the selected picture upon said screen.

6. In an automatic phonograph of the type containing a group of records, selective means operable to automatically select a record from said group and to initiate the playing thereof, a picture projecting mechanism including a screen and a lens system for projecting pictures upon said screen, a rotatable picture display wheel containing a plurality of pictures rotatable directly in the field of said lens system for projection upon said screen, each of said pictures being appropriate to an individual record, a lamp circuit controlled by said selective means and normally illuminating said screen when said records are not in use, means operated by said selective means upon the selection of a record for rotating said picture display wheel into the field of said lens system and for projecting the picture appropriate to the selected record upon said screen, and means operated by said selective means upon the selection of a record to deenergize said lamp circuit during the playing of the selected record.

7. In an automatic phonograph of the type containing a group of records, a movable turntable, a record-changing mechanism for selecting said records and for moving the selected record into a position to be received by said turntable, operating means for said turntable for moving same into a position to receive the selected record from said record-changing mechanism, a picture projecting mechanism including a screen and a lens system for projecting pictures upon said screen, a rotatable picture display wheel containing a plurality of pictures rotatable directly in the field of said lens system for projection upon said screen, each of said pictures being appropriate to an individual record, a lamp circuit adapted for directly illuminating said screen when said records are not in use, means actuated by said record-changing mechanism for rotating said picture display wheel into the field of said lens system in position to project the picture appropriate to the selected record upon said screen, and means actuated by the movement of said turntable for deenergizing said lamp circuit and projecting the selected picture upon said screen during the playing of the selected record.

JERRY LEVY.
